DESIGN FOR A BABY'S FOOD TRAY OR
ARTICLE OF ANALOGOUS NATURE

Abraham Sloan, Lynn, Mass.

Application December 12, 1946, Serial No. 135,451

Term of patent 14 years

(Cl. D44—10)

To all whom it may concern:

Be it known that I, Abraham Sloan, a citizen of the United States, residing at No. 28 Warren Street, Lynn, in the county of Essex and Commonwealth of Massachusetts, have invented a new, original, and ornamental Design for a Baby's Food Tray or Article of Analogous Nature, of which the following is a specification, reference being had to the accompanying drawing, forming a part thereof.

In the accompanying drawing Fig. 1 is a view in plan of a baby's food tray or article of analogous nature, showing my new design; Fig. 2 is a view in underside plan of said tray; and Fig. 3 is a view in sectional elevation taken along the line 3—3 of Fig. 1.

I claim:

The ornamental design for a baby's food tray

or article of analogous nature, substantially as shown.

ABRAHAM SLOAN.
